UNITED STATES PATENT OFFICE.

JOHN F. O'CONNOR, OF CHICAGO, ILLINOIS, ASSIGNOR TO WILLIAM H. MINER, OF CHAZY, NEW YORK.

HAND-BRAKE FOR RAILWAY BOX-CARS.

1,378,975.

Specification of Letters Patent. Patented May 24, 1921.

Application filed February 4, 1920. Serial No. 356,346.

To all whom it may concern:

Be it known that I, JOHN F. O'CONNOR, a citizen of the United States, residing at Chicago, in the county of Cook and State of Illinois, have invented a certain new and useful Improvement in Hand-Brakes for Railway Box-Cars, of which the following is a full, clear, concise, and exact description, reference being had to the accompanying drawings, forming a part of this specification.

This invention relates to improvements in hand brakes for railway box cars.

The object of the invention is to provide a relatively simple economical and efficient hand brake of the lever ratcheting type which is particularly adapted for use on box cars and which may be so located as to be operable from the roof of the car while at the same time, when not in use, no undesirable projections remain to interfere in any possible way with the movements of the brakeman on top of the cars.

In the drawing forming a part of this specification, Figure 1 is an end elevational view of the upper portion of a railway box car of ordinary construction showing my improvements in connection therewith. Fig. 2 is an enlarged sectional view taken through the improved hand brake on a plane substantially parallel with the end wall of the car. Fig. 3 is a vertical longitudinal sectional view corresponding substantially to the line 3-3 of Fig. 2. And Fig. 4 is an enlarged detail sectional view taken substantially on the line 4-4 of Fig. 2.

In said drawing, the box car is indicated by the reference 10, the same having the usual top running board 11, roof 12, top grab iron 13 and roof boards 14 from the side of the car to the running board 11 at the end of the car.

The improved brake, as shown, includes a hollow substantially cylindrical main or base casting A, a cover plate B, a chain winding drum C, a chain or other flexible connection D, an operating lever E, an operating handle F, a locking dog G, and means hereinafter described more specifically, for holding the lever E in retracted inoperative position.

The main casting or housing A is provided with an integral main wall 15 and depending arms 16 which are bolted to the

end plate 116 of the car. The casting A is provided with an outer partition 17, thereby forming a chamber within which the chain winding drum C is accommodated and the chain wound around the drum. The drum C is journaled at its inner end in a suitable bearing 18 formed in the wall 15, and, at its outer end, is similarly journaled in a suitable bearing 19 provided in the partition 17. A bolt 20 passes through the hub C and is adapted to hold the cover plate B in place and all of the parts in assembled relation.

The drum C is provided with a combined radially and longitudinally extending recess as indicated at 21 to thereby provide a lug 22 on the drum over which the end link of the chain is adapted to be hooked. Said link is held in assembled position after the insertion of the bolt 20, as will be apparent from an inspection of Fig. 3. The brake is so positioned that somewhat less than one-half of the upper part of the cylindrical housing or casing projects up above the roof boards 14.

For rotating the drum C, the latter is provided with an integral ratchet wheel 23 located in a plane just outside of the partition 17. Beyond the ratchet wheel 23, the drum C is provided with a section 24 of reduced diameter which forms a bearing for a hanger 25 which is loosely oscillatably mounted thereon. The hanger 25, at its lower end, is provided with an integral boss 26 which forms a pivotal support for the lower end of the arcuate operating lever E, as clearly shown in Figs. 2 and 3. The contour of the lever E is arcuate, as above indicated, and extends through approximately 180° and on its inner side is provided with a single pawl tooth 27 adapted to coöperate with the teeth of the ratchet wheel 23. Said lever E is extended outside of the housing for the brake through a suitable arcuate slot 28 and the latter is normally covered and protected from the elements by an arcuate plate shield 29 suitably attached to the lever E as indicated at 30.

It is necessary that the operating pawl assume an inoperative position when the brake is not being operated so that the brake may be released, after it has been applied, or, after it has been released will so remain until next operated. To insure this, I employ a rod 31 which is pivotally connected

to the lever E as indicated at 32, which rod extends normally vertically downward within a spring shell 33 secured to the main housing or casting of the hand brake. The 5 rod 31 carries a follower or washer 34 on its lower end between which and a fixed rib 35 is interposed the spring 36. The lever E is suitably cut away as indicated at 37 to accommodate the rod 31 as the lever E is oscillated to apply the brake. With the construction just described, it is evident that the spring 36 will react through the rod 31 in such a way as to normally hold the lever E disengaged from the ratchet wheel. At 10 the same time, the arrangement is such that the lever E may be swung into operative position with the ratchet wheel 23 and rotated or oscillated in unison therewith, in a counter-clockwise direction, through a reasonable arc which, in actual practice, will be sufficient to advance the chain winding drum an amount corresponding to two or three teeth on the ratchet wheel. By locating the rod 31, as indicated, it is evident that 15 its deflection from the vertical will be comparatively small. The first deflection will occur as the lever E is moved to engagement with the ratchet wheel and then as the oscillation of the lever E occurs in a counter-clockwise direction, the rod 31 will approach a vertical position until such time as the pivotal point 32 is on a level with the axis of the bolt 20. Thereafter, there will be 20 slight inclination toward the left, as viewed 25 in Fig. 2 but at no time will the variation 30 from the vertical be extreme or undesirable. Such inclination of the rod 31 as is necessary is accommodated by making the follower 34 slightly loose within the shell 33 and by 35 slotting the rib 35 as indicated at 38.

The locking dog G is of the gravity-controlled type and is pivoted to the lug 39 formed integral with the partition 17. Said dog G has a single tooth 40 which co-operates with the ratchet wheel 23, the handle 41 of the dog extending to the outside of the casing through a suitable slot 42. To obtain a desirable leverage, the lever E has pivoted thereto the handle F, the lever E being 45 forked as indicated at 43 for this purpose and supporting the pivot pin 44 which extends in such direction that the handle F is oscillatable about said pivot 44 in planes perpendicular to the end wall of the car. In 50 other words, the pivotal arrangement is such that the handle F will fall over on to the roof of the car as indicated by the dotted lines in Fig. 3. During the operation of the 55 brake, it is desirable that the handle F be so interlocked with the lever E that the handle will not accidentally be tilted out of its proper plane and to accomplish this in a simple manner not requiring any attention from the brakeman, the fork 43 of the 60 lever E nearest the position assumed by 65

the brakeman is provided with a notch 45 as shown in Fig. 4. The adjacent end of the handle F is provided with a corresponding tapered rib indicated at 46 adapted to swing into the notch 45 and to permit this slight 70 oscillation of the handle F on the pivot 44, the opening in the handle for the pivot pin 44 is slightly enlarged as indicated at 47 in Fig. 2.

As will be evident, when the brakeman 75 pulls on the handle F in the direction indicated by the arrow x in Fig. 1, the handle F will be properly centered and held with respect to the lever E.

With the construction shown, the brakeman is enabled to obtain considerably greater leverage than is obtainable with the ordinary types of vertical staff hand brakes now in general use. Furthermore, the improved brake presents no undesirable obstruction or projections to the passage of the brakeman from one freight car to another and the location of the brake is such that the brakeman can easily obtain a grip with his left hand while exerting his 80 strength to apply the brakes with his right hand.

Although I have herein shown and described what I now consider the preferred manner of carrying out the invention, the 95 same is merely illustrative and I contemplate all changes and modifications that come within the scope of the claims appended hereto.

I claim:

1. In a hand brake mechanism adapted for use at the top of box cars, the combination with a housing, of a member rotatably mounted therein having a ratchet wheel rigid therewith, a locking dog coöperable with said ratchet wheel, a pawl-operating lever extending through the housing upwardly, spring means normally holding said pawl-operating lever in inoperative retracted position, and a handle pivotally attached to the outer end of said lever, said lever oscillating in a plane parallel to the end wall of the car and the handle being pivotally movable on the lever in planes perpendicular to the end wall of the car. 100

2. In a hand brake mechanism adapted for use at the top of railway box cars, the combination with a housing adapted to be secured to the end wall of the car, of a chain winding drum rotatably mounted within 105 said housing about a horizontal axis and provided with a ratchet wheel, a locking dog coöperable with said ratchet wheel, a hanger oscillatably supported from said drum, a pawl-operating lever pivotally 110 mounted on said hanger and extending radially upwardly to the exterior of the housing, a handle for said lever, and spring means normally holding said operating lever in inoperative retracted position. 115

3. In a hand brake mechanism adapted for use at the top of railway box cars, the combination with a housing adapted to be secured to the end wall of the car; of means, 5 associated with said housing, for effecting tightening of a brake chain and including a lever extending upwardly to a point outside of the housing, said lever being oscillatable in a plane parallel to the end wall of 10 the car, a handle pivotally attached to said lever about an axis adapting the handle to swing in planes perpendicular to the end wall of the car, said lever and handle having coöperating recess and rib to center and 15 maintain the handle relatively to the lever when pulled in a chain-tightening direction.
4. In a hand brake mechanism adapted

for use at the top of railway box cars, the combination with a housing; of means for effecting the tightening of a brake chain including a ratchet wheel and a pawl-operating lever coöperable therewith, said lever being of substantially arcuate form and extending partly about the ratchet wheel and oscillatable in the plane of the latter, a rod 25 pivotally attached to the lever on the side thereof remote from the ratchet wheel, and spring means acting through said rod to hold said lever normally in inoperative retracted position.

In witness that I claim the foregoing I have hereunto subscribed my name this 20th day of Jan., 1920.

JOHN F. O'CONNOR.
